US00D823873S

(12) **United States Design Patent** (10) Patent No.: **US D823,873 S**
Mok et al. (45) Date of Patent: **** Jul. 24, 2018**

(54) **DISPLAY SCREEN WITH GRAPHICAL USER INTERFACE**

(71) Applicant: **Google Inc.**, Mountain View, CA (US)

(72) Inventors: **Pui See Priscilla Mok**, San Francisco, CA (US); **Christopher Paul David Johnson**, Alviso, CA (US); **Marco Quiros Viquez**, San Jose, CA (US); **Daniel Lee**, Stockholm (SE)

(73) Assignee: **Google LLC**, Mountain View, CA (US)

(**) Term: **15 Years**

(21) Appl. No.: **29/596,444**

(22) Filed: **Mar. 8, 2017**

(51) LOC (11) Cl. **14-04**

(52) U.S. Cl.

USPC **D14/486**

(58) **Field of Classification Search**

USPC D14/485-495

(57) **CLAIM**

The ornamental design for a display screen with graphical user interface, as shown and described.

DESCRIPTION

The FIGURE is a front view of a display screen with graphical user interface showing our new design. The broken lines of uneven length show the display screen and form no part of the claimed design. The broken lines of even length illustrate portions of the display screen with graphical user interface that form no part of the claimed design.

1 Claim, 1 Drawing Sheet
